SYRINGE AND DOUCHE CONTAINER

Nita Leonard and Mary Carol, Chicago, Ill.

Application February 1, 1952, Serial No. 18,342

Term of patent 14 years

(Cl. D83—1)

To all whom it may concern:

Be it known that we, Nita Leonard and Mary Carol, both citizens of the United States, residing at Chicago, county of Cook, and State of Illinois, have invented a new, original, and ornamental Design for a Syringe and Douche Container, of which the following is a specification, reference being had to the accompanying drawing, forming a part thereof, in which—

Figure 1 is a front perspective view of a syringe and douche container, embodying our new design;

Figure 2 is a top plan view thereof;

Figure 3 is a side elevational view thereof;

Figure 4 is a front elevational view thereof;

Figure 5 is an elevational view thereof taken from the side opposite that shown in Figure 3;

Figure 6 is a rear elevational view thereof; and

Figure 7 is a bottom plan view thereof.

We claim:

The ornamental design for a syringe and douche container, as shown.

NITA LEONARD.
MARY CAROL.
